CLAIM

The ornamental design for the pipe hanger, as shown and described.

DESCRIPTION

FIG. 1 is an end elevational view of a pipe hanger with the undisclosed opposite end being unornamented;

FIG. 2 is a side elevational view thereof;

FIG. 3 is a side elevational view similar to FIG. 2 from the opposite side;

FIG. 4 is a top plan view thereof; and,

FIG. 5 is an enlarged, fragmented sectional view taken along lines 5—5 of FIG. 3.

The broken line showing of pipe is for illustrative purposes only and forms no part of the claimed design.
